UNITED STATES PATENT OFFICE.

WINNIFRED H. JOHNSON, OF LOS ANGELES, CALIFORNIA.

DESIGN FOR A HOUSE-DRESS.

57,231.

Specification for Design.

Patented Mar. 8, 1921.

Application filed September 23, 1920. Serial No. 412,361. Term of patent 7 years.

To all whom it may concern:

Be it known that I, WINNIFRED H. JOHNSON, a citizen of the United States, residing at Los Angeles, in the county of Los Angeles and State of California, have invented a new, original, and ornamental Design for House-Dresses, of which the following is a specification, reference being had to the accompanying drawing, forming a part thereof.

Fig. 2 is a rear elevation of the same.

I claim:

The ornamental design for a house dress as shown.

WINNIFRED H. JOHNSON.
